Primary Examiner — Gino Colan*Assistant Examiner* — David OBrien(74) *Attorney, Agent, or Firm* — Wood Herron & Evans
LLP**CLAIM**

The ornamental design for an air freshener, as shown and described.

DESCRIPTION

FIG. 1 is an isometric view of an air freshener showing our new design;

FIG. 2 is a front elevation view thereof;

FIG. 3 left side elevation view thereof, the right side view
being identical;

FIG. 4 is a top plan view thereof;

FIG. 5 is a bottom plan view thereof; and,

FIG. 6 is a rear elevation view thereof.

The broken lines shown in the figures are for the purpose of
illustrating portions of the air freshener and form no part of
the claimed design.**1 Claim, 6 Drawing Sheets**(56)
